No. 781,494.

PATENTED JAN. 31, 1905.

A. S. COLTHARP.
EMBANKMENT PROTECTION.
APPLICATION FILED FEB. 27, 1904.

UNITED STATES PATENT OFFICE.

ALBERT STRONG COLTHARP, OF MILLIKENS BEND, LOUISIANA.

EMBANKMENT PROTECTION.

SPECIFICATION forming part of Letters Patent No. 781,494, dated January 31, 1905.

Application filed February 27, 1904. Serial No. 195,633.

To all whom it may concern:

Be it known that I, ALBERT STRONG COLTHARP, a citizen of the United States, residing at Millikens Bend, in the parish of Madison and State of Louisiana, have invented a new and useful Embankment Protection, of which the following is a specification.

This invention relates to the protection and preservation of embankments of streams or other bodies of water, more particularly to those subjected to the action of running water or the impact from waves, and has for its object to provide a revetment or protecting member which may be extended indefinitely and adjusted to conform to the rising or falling of the water.

With these and other objects in view, which will appear as the nature of the invention is better understood, the same consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention is not necessarily limited thereto, as various changes in the shape, proportions, and general assemblage of the parts may be resorted to without departing from the principle of the invention or sacrificing any of its advantages, and the right is therefore reserved of making all the changes and modifications which fairly fall within the scope of the invention and the claims made therefor.

In the drawings thus employed, Figure 1 is a perspective view of a section of an embankment with the improved protecting means applied, and Fig. 2 is a transverse section of the same. Fig. 3 represents the implements for adjusting the device upon the embankment. Fig. 4 is a perspective detail of a modified form of the "anchoring" portion of the device. Fig. 5 is a detail longitudinal sectional view taken through the upper end of one of the runners of the present device.

The improved device herein described con-

sists of a plurality of longitudinal plates 10, 50 preferably of planking or boards, connected across their rear sides by spaced transverse members 11, preferably of relatively light timbers, and held to the longitudinal plates by spikes, bolts, or other fastening means 12. 55 The longitudinal plates thus connected will constitute a section of the improved protecting means, and any required number of the sections will be placed end to end along the portion of the embankment (represented at 60 13) to be protected, with the adjacent portions of the ends preferably guarded by covering-plates 14 to prevent the entrance of water at the joints with sufficient force to undermine the sections. The sections will 65 be partially submerged by their lower edges, and to insure the retention of the sections in proper position weights 15 will be attached at suitable intervals above the surface of the water, which is indicated at 16. These weights 70 may be of any suitable kind, but will generally be bags of earth, sand, or the like, as being the most available. Each bag is provided with a loop *b* for detachable connection with a spike, pin, or projection *c*, carried near the 75 upper edge of the revetment, there being a plurality of such pins to permit of the bag being held at different locations and to permit of a plurality of weights being applied to the section whenever it may become necessary. The lower portions of the transverse members 11 will be cut away next the plates 10, so that the lower edge of the sections will closely engage the embankment 14, as shown 80 in Fig. 2, and thus prevent the water passing 85 beneath the plates and floating the sections away from the embankment. Where gullies, cavities, or other depressions *a* occur in the embankment and over which the protecting sections are required to be placed, one or more 90 bags of sand or earth 15^a will be suspended in the cavity beneath the lower edge of the section, which will fill the depression and form a "tamping" medium which will effectually close the opening and prevent the entrance of water, which would in a short time 95 completely undermine the sections and destroy their usefulness. Such weight-bags are

designed to be detachably connected to the lower edge portion of the revetment-sections in the same manner as described for the weights 15, and while a single pin only has been shown 5 near the lower edge of each section it will of course be understood that additional pins may be employed in accordance with the number of tamping devices required. The sections will preferably be maintained submerged 10 to a uniform extent, and where the depth of the water varies provision must be made to adjust the sections to correspond therewith, and an approved means for thus adjusting the sections is shown, consisting in extending the 15 transverse members 11 upwardly and providing them with apertures 17 to receive the hooked ends of rods 18, which may be readily operated by men standing upon the embankment and operating them from that position. 20 The apertures for the hooks will preferably be formed through the members 11 at an angle thereto, so that a hook having an outward trend, as at 19, may be inserted therein from one side when the sections are to be pushed 25 farther down the embankment, or a hook having an inward trend, as at 20, may be inserted from the opposite side when the sections are to be drawn farther up the embankment. If preferred, the two hooks may be arranged 30 upon one rod, as shown. The sections may be of any suitable size, but will generally be about twelve feet long and four feet wide to meet the average requirements, but may be larger or smaller to suit the varied circumstances under which they are used. 35

By this simple arrangement it is obvious that an embankment or shore may be quickly supplied with a very efficient revetment which will thoroughly protect the bank or shore from 40 erosion and which may be quickly adjusted to conform with the stage of the water and maintained at a uniform degree of submergence, so that the same extent of the protecting members may be maintained above the 45 water to receive the impact of the waves as they are thrown against the bank and effectively prevent any erosive action thereby.

While the weights 15 are ordinarily sufficient to maintain each section in place, it 50 sometimes becomes necessary to positively anchor the device, and to provide for this contingency an opening 21 is formed through the upper projected end of the transverse member or runner 11 for the reception of a pin 55 22, (shown in Fig. 2 of the drawings,) which is designed to be driven through the opening and into the embankment so as to positively anchor the section against slidable movements up and down upon the embankment. In addition to the anchoring-pin 22 I also propose to employ another anchoring-pin 23, (best shown in Fig. 4 of the drawings,) said pin being intermediately pivoted, as at 24, to one of the upright edges of the upper projected

end of the runner and capable of being alined 65 transversely with the runner when the section is being handled and fitted in place and also capable of being turned at substantially right angles to the runner in order that its opposite end may be driven into the embankment 70 after the section has been properly set in place. It will of course be understood that each runner is to be provided with an opening 21 for the reception of a pin 22 and also with the pivotal anchoring-pin 23, so that 75 either or both of these anchoring devices may be employed. When the pin 22 is employed, the section cannot be readily slid up and down, as it is necessary to pry up the upper ends of the runners so as to loosen the pins 22 before the section can be raised or lowered by 80 means of the hooked devices 18. When the pivotal anchoring-pins 23 are employed and the pins 22 omitted, the section may be readily slid up or down, as the pivotal pin will turn 85 under excess pressure and draw out of the embankment when a strong pull or push is applied to the section through the medium of the hooked devices 18 and can readily be again driven into the embankment when the 90 section has been set to the desired new location, wherefore it will be understood that the pivotal anchoring-pins have an advantage over the pins 22. Moreover, the pins 23 are 95 positively carried by the runners and are therefore always in position for being conveniently driven into the embankment, while the pins 22 are assembled with the runners only when they have been driven through the 100 openings 21, and therefore do not form quite so convenient anchoring means as that afforded by the pivotal pins. Under ordinary strains the weights and the pivotal pins 23 are sufficient to hold each section in place; but should the strength of the current or waves 105 become excessively violent the pins 22 may be employed in addition to the pivotal pins to insure a positive anchoring of the device. Located between the transverse perforation 110 17 and the upper extremity of each runner is a fixed reinforcing-pin 25, which is designed to prevent splitting of the extremity of the runner under the pulling strains occasioned by the hooked devices 18 when raising each section. 115

Having thus described my invention, what I claim is—

1. A protection for embankments consisting of protecting members disposed longitudinally of the same and partially submerged, 120 weights applied to said protecting member above the water, and means for adjusting said protecting member to maintain the same submerged to a uniform extent.

2. A protection for embankments consisting of protecting members disposed longitudinally of the same and partially submerged, 125 weights detachably applied to said protecting

member above the water, and means for adjusting said protecting member to maintain the same submerged to a uniform extent.

3. A device of the class described comprising a rigid revetment-section provided at its upper end with means for anchoring the same flat against an embankment, and a weighted tampering element connected to the lower edge portion of the section and projected downwardly beyond the same to engage and fill a washout portion of the embankment below the revetment-section.

4. A protection for embankments consisting of a plurality of protecting members disposed longitudinally of the same and partially submerged, and guard-plates for covering the adjacent ends of the protecting members.

5. A protection for embankments consisting of plates disposed longitudinally of the same and connected across their rear sides with transverse members, the sides of said transverse members next the longitudinal plates being cut away to bring the rear sides of the same in substantial alinement with the rear faces of the transverse members, whereby the lower edge of the longitudinal plates will closely engage the embankment when applied thereto.

6. A protection for embankments consisting of a plurality of members formed of longitudinal plates connected across their rear sides and adapted to be placed end to end upon the embankment to be protected and partially submerged, and with guard-plates covering the contiguous portions of the ends of the protecting members.

7. A protection for embankments consisting of protecting members disposed longitudinally of the same and partially submerged, means for adjusting said protecting member to maintain the same submerged to a uniform extent, and an anchor means carried by said protecting member for forcing into the embankment.

45 8. A protection for embankments consisting of protecting members disposed longitudinally of the same and partially submerged, means for adjusting said protecting member to maintain the same submerged to uniform extent, and anchor members movably connected to said protecting member for extension therefrom into the embankment.

9. A protection for embankments consisting of plates disposed longitudinally of the same and connected across their rear sides with transverse members, with the transverse mem-

bers extending above the longitudinal plates, and anchor means connected to said extended ends for forcing into the embankment.

10. A protection for embankments consisting of plates disposed longitudinally of the same and connected across their rear sides with transverse members, with the transverse members extending above the longitudinal plates, and anchor members movably connected to said extended ends for projection therefrom into the embankment.

11. A device of the class described consisting of a revetment-section provided upon its under side with runners which are projected at the upper edge of the section, each upper projected end of the runner being provided with an inclined perforation extending entirely through the runner in the plane of the section and also having another perforation extending through the projected end of each runner at an angle to the plane of the section for the reception of an anchoring-pin.

12. A device of the class described consisting of a revetment-section having runners upon its under side which are projected at the upper edge of the section, the projected end of each section being provided with an inclined perforation extending entirely through the runner in the plane of the section, and a fixed reinforcing-pin piercing the upper end of each runner above the perforation therein.

13. A device of the class described consisting of a revetment-section having runners upon its under side with their upper ends projected above the section, and anchoring-pins intermediately pivoted to the upright edges of the upper projected ends of the runners.

14. A device of the class described consisting of a revetment-section provided upon its under side with runners which are projected above the upper edge of the section, said projected ends of the runners being provided with perforations intersecting the same at an angle to the plane of the section for the reception of an anchoring-pin, and other anchoring-pins pivoted intermediate of their ends to the upright edges of the projected ends of the runners.

In testimony that I claim the foregoing as my own I have hereto affixed my signature in the presence of two witnesses.

ALBERT STRONG COLTHARP.
